(57) **CLAIM**

The ornamental design for a squeeze-type juice extractor, as shown and described.

DESCRIPTION

FIG. 1 is a perspective view of a squeeze-type juice extractor of the present invention;

FIG. 2 is another perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.
